(57) **CLAIM**

The ornamental design for a customizable container, as shown and described.

DESCRIPTION

FIG. 1 is a perspective view of a customizable container in accordance with a first embodiment of our design;

FIG. 2 is a front elevational view of the customizable container of FIG. 1;

FIG. 3 is a rear elevational view of the customizable container of FIG. 1;

FIG. 4 is a left side elevational view of the customizable container of FIG. 1;

FIG. 5 is a right side elevational view of the customizable container of FIG. 1;

FIG. 6 is a top plan view of the customizable container of FIG. 1;

FIG. 7 is a bottom plan view of the customizable container of FIG. 1;

FIG. 8 is an exploded view of the customizable container of FIG. 1;

FIG. 9 is a cross sectional view of the customizable container of FIG. 1, taken in the plane 9-9 of FIG. 6.

FIG. 10 is a perspective view of a customizable container in accordance with a second embodiment of our design;

FIG. 11 is a front elevational view of the customizable container of FIG. 10;

FIG. 12 is a rear elevational view of the customizable container of FIG. 10;

FIG. 13 is a left side elevational view of the customizable container of FIG. 10;

FIG. 14 is a right side elevational view of the customizable container of FIG. 10;

FIG. 15 is a top plan view of the customizable container of FIG. 10;

FIG. 16 is a bottom plan view of the customizable container of FIG. 10;

FIG. 17 is an exploded view of the customizable container of FIG. 10;

(Continued)

FIG. 18 is a cross sectional view of the customizable container of FIG. 10, taken in the plane 18-18 of FIG. 15. FIG. 19 is a perspective view of a customizable container in accordance with a third embodiment of our design; FIG. 20 is a front elevational view of the customizable container of FIG. 19; FIG. 21 is a rear elevational view of the customizable container of FIG. 19; FIG. 22 is a left side elevational view of the customizable container of FIG. 19; FIG. 23 is a right side elevational view of the customizable container of FIG. 19; FIG. 24 is a top plan view of the customizable container of FIG. 19; FIG. 25 is a bottom plan view of the customizable container of FIG. 19; FIG. 26 is an exploded view of the customizable container of FIG. 19; and FIG. 27 is a cross sectional view of the customizable container of FIG. 19, taken in the plane 27-27 of FIG. 24. The broken lines having consistent dash lengths (dash-dash-dash) represent portions of the customizable container that form no part of the claimed design.
